WITNESS: L. J. Hammand.

UNITED STATES PATENT OFFICE

WILLARD L. HARTNELL, OF BELOIT, WISCONSIN, ASSIGNOR TO YATES-AMERICAN MACHINE COMPANY, OF BELOIT, WISCONSIN, A CORPORATION OF DELAWARE

FEEDING DEVICE FOR WOODWORKING MACHINES AND THE LIKE

Application filed January 24, 1930. Serial No. 423,201.

This invention relates to certain novel improvements in feeding devices for woodworking machines and the like, and has for its principal object the provision of an improved construction of this character which will be highly efficient in use and economical in manufacture.

Among the salient objects of my invention is to provide a feeding device that will operate on the side edges of the material being handled by the feeding device.

Another object of the invention is to provide a device of the above described character which will be so arranged that the material to be handled thereby may be directed thereto from a position thereabove.

Another object of the invention is to provide a device of the above described character that will be constantly forced in a predetermined direction in order to insure proper engagement of the device with the material to be handled thereby.

A further object of the invention is to provide a device of the above described character which will be so constructed that portions thereof will be disposed at varied distances from the center of rotation, and in which other portions will be equidistantly spaced from the center of rotation to provide an annular rolling surface.

Other objects will appear hereinafter.

The invention consists in the novel combination and arrangement of parts to be hereinafter described and claimed.

The invention will be best understood by reference to the accompanying drawing showing the preferred form of construction and in which:

Fig. 1 is a side view, drawn partly in elevation and partly in section, depicting the preferred form of construction for my invention;

Fig. 2 is a top plan view of my propelling member;

Fig. 3 is a sectional view taken substantial-

ly on the line 3—3 on Fig. 2 depicting my improved propelling member in propelling position;

Fig. 4 is a view similar to Fig. 3 depicting the parts in another of the operative positions; and

Fig. 5 is a view partly in elevation and partly in section looking in the same direction as Figs. 3 and 4 depicting the embodiment of the invention illustrated in Fig. 1.

In the accompanying drawing wherein I have illustrated the preferred form of construction for my invention, 10 generically indicates a feed conveyor embodying rolls 11 which are preferably of the driven type. Extending up from the roller feed conveyor 10 are side walls 12 and 13 which define therebetween a bin or material receiving space 14. The bin or material receiving space 14 is intended to be slightly wider than the material to be handled in the device, and this material in the present instance is in the form of boards indicated by 15. If desired, the side walls of the bin 14 may be arranged to be adjustable in order that material of different widths may be handled in the device.

A stud shaft 16 extends into the bin 14 from the wall 12, and pivotally mounted thereon is an arm 17. A roller 18 is rotatably mounted at the outer end of the arm 17, and the roller 18 rests on the boards 15 rested on the rollers 11 of the feed conveyor 10 and serves to hold these boards 15 in engagement with said rollers.

At the forward end of the wall 12 is a supporting bracket 19 having slots 20 therein. Extended through the slots 20 are bolts 21 which are mounted in the bunt block 22. Nuts 23 are provided on the bolts 21, and by tightening the bolts 23, the bunt block 22 may be locked in various adjusted vertical positions to regulate the amount of opening between the lower edge of the bunt block 22 and the upper edge of the feed roller 10. The

amount of this opening is preferably slightly greater than the thickness of the boards 15 to be handled by the device.

My improved device includes a mechanism for driving the boards from the feed conveyor 10 into a woodworking machine or the like, and includes the following mechanisms. A suitable supporting bed 24 is provided which has guideways 25 therein in which the ribs 26 on the supporting member 27 are slidably mounted. On the supporting bed 24 is a boss 28. Mounted on the supporting member 27 in alignment with the boss 28 is a boss 29. A rod 30 is fixed to the boss 29 and is freely extended through an opening in the boss 28. A spring 31 is disposed around the rod 30 between the bosses 28 and 29 and acts on the boss 29 to force the supporting member 27 outwardly away from the supporting bed 24 into engagement with the stop 32.

A bevel gear 33 is rotatably supported by the supporting member 27 and a shaft 34 is extended through this bevel gear 33 and is keyed thereto as indicated at 35. Therefore, the bevel gear 33 will be movable with the supporting member 27 relative to the shaft 34 and will also be rotatable with said shaft 34.

30. Mounted on a stud shaft carried by the supporting member 27 is a bevel gear 36 that meshes with the bevel gear 33. Vertically aligned bearings 37 and 38 are provided on the supporting member 27 in which a vertically extending shaft 39 is journaled. At the lower end of the shaft 39 is a bevel gear 40 which meshes with the bevel gear 36. Therefore, when the shaft 34 is rotated to rotate the bevel gear 33, the bevel gear 36 will be rotated, and therefore the bevel gear 40 and the shaft 39.

Fixed to the upper end of the shaft 39 is a member 41. The member 41 embodies a portion 42 which is part of the circumference of a circle drawn from the center of the shaft 39, and also includes a portion 43 which is eccentric with respect to such circle, and these portions include a portion 44 which merges the portion 43 with the portion 42 along an even curve. Depending from the member 41 along the portion 42 thereof is a section 45. Another member 46 is provided which includes a section 47 that co-operates with the portion 42 to complete the circle heretofore referred to. The member 46 is also cut away, as indicated at 63, in order that the member 46 may be fitted about the shaft 39 below the member 41, the combined thickness of the members 41 and 46 being equal to the thickness of the boards 15. Studs 49 are fixed on the member 41 and are freely extended through openings in the member 46 and have nuts 50 thereon. Springs 51 are disposed about the studs 49 between the nuts 50 and the lower surface of the member 46, and serve to nor-

mally urge the member 46 into the position depicted in Figs. 3 and 5.

As the boards 15 are fed into the bin 14, they collect on the rollers 11 and the portion 47, as shown in Fig. 5. However, the weight of the roller 18 will force the boards downwardly into the position depicted in Fig. 4 and therefore the edge of the lowermost board 15 will be engaged by the eccentric surface 43. As the shaft 39 rotates the members 41 and 46 in a counter-clockwise direction, the side edge of the lowermost board 15 is engaged by the portion 44 and then by the portion 42. During the time this lowermost board is engaged by the portion 42 the springs 51 are apt to move the member 46 into the position depicted in Fig. 3, and it is therefore manifest that the lowermost board 15 is engaged by the sections 42 and 47 which co-operate to provide a circle and therefore the lowermost board 15 will be propelled forwardly as the shaft 39 is rotated. The roller provided by the sections 47 and 42 is urged into engagement with the lowermost board 15 by the spring 31 which is compressed as the less eccentric portions of the portions 43 and 44 engage the lowermost board 15, for manifestly this will move the supporting structure 27 relative to the supporting bed 24.

As best illustrated in Fig. 1, the device providing the driving roller is mounted in juxtaposition to the bunt block 22. Therefore, as the lowermost board is driven forwardly, it will engage the first co-operating pair of feed rolls 52 and 53. The feed rolls 52 and 53 are mounted on the shafts 54 and 55. A similar pair of shafts 56 and 57 are provided forwardly of the shafts 54 and 55, and these shafts 56 and 57 also carry feed rollers, and as the lowermost board 15 is driven forwardly, it is engaged by these feed rollers and forced into the machine. The shafts supporting the feed rollers are mounted in vertically adjustable blocks 58 and 59 which have a spring 60 disposed therebetween. A spring 61 acts on the block 58 to force the same toward the block 59, and a spring 62 similarly acts on the block 59 to force said block 59 toward the block 58 and movement of the blocks toward each other is limited by the spring 60 which prevents the blocks engaging each other but which permits the rollers carried by the shafts journaled in the blocks to tightly engage the board disposed therebetween in order to propel the same forwardly.

It is manifest from the foregoing description that I have provided a propelling device which will be eccentric for a portion of its revolution to permit an article to be fed thereinto but which will also operate to be substantially annular in order to drive the article forwardly. It is manifest that after one board has been driven from the machine another board will be inserted into the device

in substantially the manner set forth and additional boards will be continually fed into the bin 14 in any desired manner.

While I have illustrated and described the 5 preferred form of construction for carrying my invention into effect, this is capable of variation and modification without departing from the spirit of the invention. I, therefore, do not wish to be limited to the precise details 10 of construction set forth, but desire to avail myself of such variations and modifications as come within the scope of the appended claims.

Having thus described my invention, what 15 I claim as new and desire to protect by Letters Patent is:

1. A feeding device for woodworking machines comprising propelling means adapted to engage the side edges of the boards or the 20 like to be propelled, means for supporting said propelling means, and yieldable means for forcing said propelling means toward the boards or the like to be propelled thereby, said propelling means including two non- 25 circular members cooperating in a certain position to form a circular member and one of which is adapted for moving said propelling means in a direction away from the boards or the like to be propelled thereby to permit said boards or the like to be engaged by said circular propelling member.

2. A feeding device for woodworking machines comprising a supporting bin, means for forcing articles in said supporting bin 30 toward the lower edge thereof, means at one end of said supporting bin for preventing movement of said articles from said end of said bin, means for forcing said articles past said last named member including propelling 35 means, said propelling means comprising supporting means, yieldable means connecting said supporting means and said propelling means, said propelling means including two non-circular rotatable members cooperating 40 in a certain position to form a circular member and arranged one above the other, the upper one of said members being adapted for engaging said articles to move said propelling means in a direction away from said articles to be engaged by said circular member and 45 propelled thereby.

3. In a device of the character stated, a supporting bin, means for forcing articles in said supporting bin toward the lower edge thereof, means at one end of said supporting bin for preventing movement of said articles from said end of said bin, means for forcing said articles past said last named member including propelling means adapted to engage the 55 side edges of said articles, said propelling means comprising rotatable means and supporting means for said rotatable means, and yieldable means acting on said supporting means for urging said propelling means into 60 propelling position, said rotatable means in-

cluding a shaft and propelling members eccentrically mounted on said shaft, one of which is adapted to engage the articles to be propelled whereby said propelling means may be moved against the action of said urging 70 means to permit the other of said eccentric propelling members to move into propelling position to provide with the first named eccentric member a circular propelling member.

4. A feeding device for woodworking machines comprising propelling means adapted to engage the side edges of the boards or the like to be propelled, means for supporting said propelling means, and yieldable means for forcing said propelling means toward the 75 boards or the like to be propelled thereby, said propelling means including two non-circular members cooperating in a certain position to form a circular member and one of which is adapted for moving said propelling 80 means in a direction away from the boards or the like to be propelled thereby to permit said boards or the like to be engaged by said circular propelling member, said members being arranged one above the 85 other, and yieldable means connecting said members whereby when said boards or the like are moved onto the lower of said members said lower member will be moved away from the upper member so that the upper 90 member will tend to move said projecting means away from the boards to permit said circular member to engage said boards or the like when said boards are moved off said lower member and said lower member is moved 95 back into position parallel with said upper member.

5. In a device for feeding boards to a woodworking machine, a power-driven feed roll for engagement with the edge of each 100 board, said roll having a peripheral section which is yieldable downwardly to facilitate movement of a board downwardly into opposition to the roll.

6. In a device for feeding boards to a wood- 110 working machine, a power-driven feed roll having a circular lower portion for feeding a board and an eccentric upper portion for effecting engagement of the lower portion with the board.

7. In a device for feeding boards to a wood- 115 working machine, a power-driven feed roll for engagement with the edge of each board, and cam means at the location of the roll for properly positioning the roll with respect to 120 the edge of each board.

8. In a device for feeding boards to a wood- 125 working machine, means for supporting a stack of boards, a power-driven feed roll engageable with the edge of the lowermost board for feeding the same forwardly from beneath the stack, and means at the location of the feed roll for automatically positioning the latter in operative relation to the edge of 130 the lowermost board.

9. In a device for feeding boards to a wood-working machine, means for supporting a stack of boards, a power-driven feed roll engageable with the edge of the lowermost board for feeding the same forwardly from beneath the stack, and means mounted on the feed roll for automatically positioning the latter in operative relation to the edge of the lowermost board.
10. In testimony whereof I affix my signature.

WILLARD L. HARTNELL.
